UNITED STATES PATENT OFFICE

2,434,865

TWO-WAY RAIL ANCHOR

Frederick A. Preston, Lake Forest, and Harold G. Warr, Park Ridge, Ill., assignors, by direct and mesne assignments, to Poor & Company, Chicago, Ill., a corporation of Delaware

Application August 9, 1944, Serial No. 548,648

5 Claims. (Cl. 238—327)

1

This invention relates to improvements in rail anchoring devices, and particularly to anchoring devices adapted to cooperate with a rail supporting element to prevent lengthwise movement of the rail relative to said supporting element.

One of the objects of the invention is to provide improvements in devices of the above character which make it practicable to provide a two-way anchor device constructed to exert its principal grip on the rail diagonally through the rail base from the lower web fillet at one side of the rail to the outer edge of the rail base flange at the other side of the rail, and to also extend into the space between the rail base and the top surface of an underlying cross tie so as to embracingly engage the forward and rear edge portions of a tie plate interposed between the rail and the cross tie.

Two-way anchoring devices constructed to embracingly engage the forward and rear edges of a tie plate have been heretofore proposed, but such anchor devices have been provided with hook-shaped jaws to grip the top and bottom surfaces of the rail base flange at one side of the rail. In such anchor devices, the under rail or transverse body portions of the device are provided with separate jaws formed to grip the top and bottom surfaces of the rail base flange at one side of the rail. However, in the present improvement there is but a single jaw at one side of the rail which cooperates with both transverse body portions of the anchor. It is, therefore, a specific object of the present invention to so construct and arrange the single jaw portion that it will equalize the gripping pressure exerted by both of the transverse body portions.

Another object is to provide a two-way anchor device of the specific type herein shown in which the single rail gripping jaw at one side of the rail is formed to bear on the fillet at the junction of the vertical web of the rail with the base portion thereof and is of such length that the jaw can be formed from a bar of greater width than thickness and arranged edgewise relative to the web of the rail to provide the necessary gripping force for both under rail body portions of the anchor and at the same time provide the required flexibility and resilience transversely of the rail to avoid localized distortions of the jaw and to permit the anchoring device to be readily applied to rails having base portions of different widths and thickness.

Another and more specific object of the invention is to form a two-way anchor of the above general type with a single jaw for engagement

2

with the rail at one side thereof and cooperating with two spaced apart under rail body portions, which jaw is formed to provide a centrally disposed bearing surface which together with the length of the jaw functions to prevent localized distortion of the jaw during the application of the device to a rail.

Another object of the invention is to provide an anchor of the above character which is made from a bar of rectangular cross section with one of its longitudinal faces rounded and in which the rounded surface is so disposed as to provide a suitable surface for bearing against the lower web fillet of the rail, the configuration of the anchor device being such that the flat longitudinal faces of the bar in that portion thereof which extends beneath the rail base is positioned to bear against the forward and rear faces of the tie plate.

20 The invention is illustrated in two preferred embodiments in the accompanying drawings wherein:

Fig. 1 is a transverse section taken through the base portion of a railroad rail showing a rail anchor device constructed in accordance with this invention applied thereto in a position to embracingly engage a tie plate interposed between the base portion of the rail and the top surface of an underlying cross tie.

25 Fig. 2 is a plan view of the several cooperative elements included in the structure of Fig. 1.

Fig. 3 is a view in elevation taken from the left of Fig. 1.

30 Fig. 4 is a view in elevation of a metal bar provided with the jaw bent to provide the desired curvature of the jaw portion, but before formation of the anchor body is completed.

Fig. 5 is a cross section taken on line 5—5 of Fig. 4; and

35 Fig. 6 is a view similar to Fig. 1 but illustrating a modified construction in which the under rail body portions of the anchor are formed at their free ends with hooked portions adapted to be engaged over the upper longitudinal corner of the rail base.

40 Referring first to Figs. 1 to 5, inclusive, of the drawings: The base portion of a railroad rail is designated by the reference numeral 10. It is supported on a supporting structure comprising a cross tie 11 and a tie plate 12, the latter of which is interposed between the rail base 10 and the top surface of the cross tie 11. The tie plate, herein illustrated, is formed to provide an inclined rail seat 13 and is provided at opposite sides of said seat with upstanding ribs 14 and 15 for

abutting against opposite longitudinal edges of the rail base 10. The tie plate is also provided with four spike openings designated 16, adapted to receive rail retaining members 17. In the present illustration the rail retaining members consist of driven spikes of rigid construction, but any form of retaining members, such as screws, flexible spikes, and/or clips may be used. The width of tie plate 12, as herein illustrated, is somewhat less than the width of the cross tie 11. Consequently, there are spaces designated 18 and 19, as shown best in Fig. 3, intervening between the bottom surface of the rail base 10 and the top surface of the cross tie 11 adjacent the forward and rear faces of the tie plate 12.

The rail anchor device, as illustrated in Figs. 1 to 5, inclusive, is made from a metal bar of general rectangular configuration which is of greater width than thickness and formed with one of its narrow faces rounded as indicated by the reference numeral 20. The said bar is formed with a substantially straight bearing portion midway between its ends and is bent to provide a relatively long bowed portion 21 and spaced arms 22 and 23. The bowed portion 21 constitutes an upper jaw of the anchor device and the rounded surface 20 as the substantially straight central portion of the bar is adapted to bear against the fillet 24 at the junction of the web 25 of the rail with the base portion 10. The said arms 22 and 23 are then formed with bends 26 and 27 so that the jaw portion 21, together with the said bends, provide hook-shaped portions which embrace one flange of the rail and bear against fillet 24, as previously described. The other portion of the arms 22 and 23 constitute body portions which extend across beneath the rail base and abut against the forward and rear edges of the tie plate 12 within the spaces 18 and 19. The ends of both under rail body portions of the anchor are offset upwardly, as indicated at 28 and 29, so as to provide locking shoulders for engagement with the lower longitudinal edge of the rail base.

In applying the anchor device to the rail the shoulder ends of the body portions 22 and 23 are passed beneath the rail until the hook-shaped jaw portion 21 engages the top inclined surface of the rail base. This position will be assumed before the locking shoulders 28 and 29 engage over the other edge of the rail base. The jaw portion 21 of the anchor is then forced upwardly on the rail base to bear against the fillet 24. This force is preferably applied by striking the bends 26 and 27 of the anchor device with a track sledge or other suitable implement. During this applying movement the bowed jaw portion 21 will be flexed substantially throughout its full length so as to permit the under rail body portions 22 and 23 to move transversely of the rail base a distance sufficient to permit the locking shoulders 28 and 29 to snap up over the other edge of the rail base. The said application of force also tends to flex the large bends 26 and 27 transversely of the rail to some extent so that the combined resilience of the bends 26 and 27 and the bowed jaw portion 21 exerts a resilient grip on the rail which extends diagonally through the rail base from the fillet 24 to the lower corner of the rail base flange at the other side of the rail. The length of the jaw 21 is such that it can be positioned edgewise against the fillet 24 and flexed transversely of its greatest width a distance sufficient to permit the application of the anchor device to rails having oversized base flanges. This flexing of the jaw 21 transversely of the rail also

tends to increase the spacings between the under rail body portions 22 and 23 and thereby facilitates application of the anchor device to oversized tie plates. The application of the anchor device to the base flange of the rail also effects a slight spreading of the jaw 21 relative to the transverse body portions 22 and 23 and thereby effects a vertical gripping action between the end of the jaw 21 and the under rail body portions of the anchor device, which gripping action is uniform in relation to both under rail body portions. This vertically exerted force serves, in addition to resisting the creeping movement of the rail to hold the locking shoulders 28 and 29 in their locking positions.

Referring now to the modified embodiment shown in Fig. 6: The modified anchor device, for the most part, may be and preferably is identical with the constructions of the previous embodiment. The only difference being that instead of forming the free ends of the under rail body portions with offset shoulders, as indicated in Fig. 1, the free ends of the body portions designated 30 and 31 are bent to form return hooks 32 and 33 adapted to engage over the upper corner portion 34 of the rail base flange. The combined flexing of jaw 21 and the bends 26 and 27 of the modified anchor device permit transverse flexing of the anchor sufficient to apply the return hook portions 32 and 33 over the upper corner 34 of the rail base.

While the invention is illustrated herein in connection with certain conventional rail base and supporting structures, it will be obvious that the anchor device can be constructed to accommodate supporting structures of various character. It will also be obvious that the embodiments of the invention herein shown may be otherwise varied in construction without departure from the spirit of the invention. Consequently the invention is not to be limited by the specific constructions shown and described except where those constructions are included in the claims.

We claim:

45. 1. A unitary device adapted to cooperate with a railroad rail supporting structure to resist both forward and rearward movements of the rail relative to said supporting structure, comprising two body portions for extending transversely of the rail beneath the base thereof and a connecting bar for connecting said body portions; the said body portions being positioned to abut against opposite faces of the said rail supporting structure and provided with means for locking engagement with the rail, and the said connecting bar being positioned to extend lengthwise of the rail across said rail supporting structure and formed with a rounded edge to bear against a curved fillet at the junction of the web of the rail and the base portion thereof and being formed also with a straight portion midway between the bodies and bowed toward the rail so that the said bar will bear only against the said fillet at the location of said straight portion.
50. 2. A unitary device adapted to cooperate with a railroad rail supporting structure to resist both forward and rearward movements of the rail relative to said supporting structure, comprising a bar of greater width than thickness having a rounded surface along one longitudinal edge thereof and a flat surface along the opposite edge and bent to form two body portions for extending transversely of the rail beneath the base thereof and a connecting bar for connecting the ends of said body portions at one side of the rail;
55. 3. A unitary device adapted to cooperate with a railroad rail supporting structure to resist both forward and rearward movements of the rail relative to said supporting structure, comprising a bar of greater width than thickness having a rounded surface along one longitudinal edge thereof and a flat surface along the opposite edge and bent to form two body portions for extending transversely of the rail beneath the base thereof and a connecting bar for connecting the ends of said body portions at one side of the rail;
60. 4. A unitary device adapted to cooperate with a railroad rail supporting structure to resist both forward and rearward movements of the rail relative to said supporting structure, comprising a bar of greater width than thickness having a rounded surface along one longitudinal edge thereof and a flat surface along the opposite edge and bent to form two body portions for extending transversely of the rail beneath the base thereof and a connecting bar for connecting the ends of said body portions at one side of the rail;
65. 5. A unitary device adapted to cooperate with a railroad rail supporting structure to resist both forward and rearward movements of the rail relative to said supporting structure, comprising a bar of greater width than thickness having a rounded surface along one longitudinal edge thereof and a flat surface along the opposite edge and bent to form two body portions for extending transversely of the rail beneath the base thereof and a connecting bar for connecting the ends of said body portions at one side of the rail;
70. 6. A unitary device adapted to cooperate with a railroad rail supporting structure to resist both forward and rearward movements of the rail relative to said supporting structure, comprising a bar of greater width than thickness having a rounded surface along one longitudinal edge thereof and a flat surface along the opposite edge and bent to form two body portions for extending transversely of the rail beneath the base thereof and a connecting bar for connecting the ends of said body portions at one side of the rail;
75. 7. A unitary device adapted to cooperate with a railroad rail supporting structure to resist both forward and rearward movements of the rail relative to said supporting structure, comprising a bar of greater width than thickness having a rounded surface along one longitudinal edge thereof and a flat surface along the opposite edge and bent to form two body portions for extending transversely of the rail beneath the base thereof and a connecting bar for connecting the ends of said body portions at one side of the rail;

the flat edge of the bar in the said body portions being positioned to abut against opposite faces of the said rail supporting structure and the said body portions being provided with means for locking engagement with the rail, and the said connecting bar being positioned to extend lengthwise of the rail across said rail supporting structure and bowed toward the web of the rail and positioned for bearing engagement of said rounded surface only at a location midway between said body portions, against a fillet at the junction of said web and the base portion of the rail.

3. A unitary device adapted to cooperate with a rail supporting structure to resist both forward and rearward movements of the rail relative to said supporting structure, comprising a bar of greater width than thickness bent to form two body portions for extending transversely of the rail beneath the base thereof and a connecting bar for connecting said body portions; the said body portions being positioned to abut against opposite faces of the said rail supporting structure and provided with means for locking engagement with the rail, and the said connecting bar being positioned to extend lengthwise of the rail across said rail supporting structure and formed with a rounded edge to bear against a curved fillet junction of the web of the rail and the base portion thereof and being formed also with a straight portion midway between the bodies and bowed toward the rail so that the said bar will bear only against said fillet at the location of said straight portion.

4. A unitary device adapted to clamp a rail base and engage forward and rear faces of a rail supporting structure to resist lengthwise movement of the rail relative to said structure, comprising a flat bar of greater width than thickness having a rounded surface along one longitudinal edge thereof and bent to provide two body portions which extend flatwise across beneath the rail base and a connecting bar which connects the ends of said body portions at one side of the rail and extends lengthwise of the rail across said rail supporting structure and is bowed from end to end in the direction of said greater width and positioned for engagement of said rounded surface, at a location midway between said body portions, with a fillet at the junction of the central web of the rail with the base thereof and the ends of said body portions at the other side of the rail being formed with locking shoulders for engagement with a lower longitudinal corner

portion of the rail base, whereby a grip exerted by the unitary device extends diagonally through the rail base from the midway bearing at the central portion of said connecting bar on said fillet to the said lower longitudinal corner portion of the rail base flange at the other side of the rail, and whereby the flexing of said connecting bar at opposite sides of its midway bearing exerts equal clamping actions on said body portions both vertically and transversely of the rail.

5. A unitary device adapted to clamp a rail base and engage forward and rear edge faces of a tie plate on which the rail is seated to resist lengthwise movement of the rail relative to said tie plate, comprising a bar of greater width than thickness having a rounded surface along one longitudinal edge thereof and a flat surface along the opposite edge and bent to provide two body portions which extend flatwise across beneath a rail base with said flat edge portion of the bar engaging the tie plate and a connecting bar which extends lengthwise of the rail across said supporting structure and is bowed from end to end in the direction of said greater width and positioned for edgewise engagement of said rounded edge at a location midway between said body portions with a fillet at the junction of the central web of the rail with the base thereof and the other ends of said body portions being formed with locking shoulders for engagement with a lower longitudinal corner portion of the rail base, whereby a grip exerted by the unitary device extends diagonally through the rail base from the central portion of said connecting bar on said fillet to the said lower longitudinal corner portion of the rail base flange at the other side of the rail.
